UNITED STATES PATENT OFFICE.

HENRY MOECKER, JR., OF HOMEWOOD, AND OTTO HAMMERMEISTER AND THEODORE THOMPSON, OF HARVEY, ILLINOIS, ASSIGNEES TO AMERICAN STOVE COMPANY, OF ST. LOUIS, MISSOURI, A CORPORATION OF NEW JERSEY.

RIGHT AND LEFT HAND OVEN GAS RANGE.

Application filed August 29, 1925. Serial No. 53,292.

This invention relates to improvements in right and left hand oven gas ranges, and it pertains to a construction that is capable of being put together and produce a gas range with either a right or left hand oven.

The primary object of this improvement is to enable a manufacturer to so construct the parts of his gas range that he can make it without any change in the parts into either a left hand or a right hand oven range.

Heretofore manufacturers have found it necessary to manufacture right hand oven ranges, and left hand oven ranges, which requires a great deal of expense in the way of tools and parts, which it is the object of our present improvement to avoid.

With a range constructed of parts as hereinafter defined, the manufacturer only requires tools and parts for one type of range, and these parts are so constructed that he can make the range either a left or a right hand range.

While it is possible after the range is put together, to take it apart and re-arrange the construction to place the oven on the opposite side of the range, the present improvement is adapted to save expense to the manufacturer, and make it convenient for him to produce either of the said types of range.

30 In the accompanying drawings,

Figure 1 is a horizontal sectional view taken through a gas range just above the top for the oven burners with the parts in position to form a right hand range.

35 Fig. 2 is a vertical sectional view taken on the line 2-2 of Figure 1.

Fig. 3 is a rear view of a right hand oven range showing the parts at the rear of the range in proper position.

40 Fig. 4 is a rear view showing the parts in the rear in reversed positions, and therefore a left hand range is the result.

Fig. 5 is a perspective view looking at the gas range from the side and rear of the oven and the rear of the oven burners, the parts shown in disassembled relation.

45 Fig. 6 is a detached perspective view of the burner, attachments therefor and the outer wall of the oven.

50 Fig. 7 is a perspective view of part of the inner wall of the oven and the burner manifold passing through the same.

In carrying out the present improvements, the parts which constitute the gas range, are

so constructed that by reversing their positions, they can be used to construct either a right or left hand range. By reference to the drawings, this improved range comprises the part 1, that contains the oven burners 2, that have their supply pipes 3 running to the front portion of the range and receiving their fuel from a supply pipe 4, which is located in front of the burners. In the form of range here shown, preferably the gas supply is through a pipe 5, from the rear of the range, though, of course, it may come from other positions without departing from the present invention.

In Figs. 1, 2 and 4, the parts are shown as arranged to construct a right hand oven range, the oven being indicated by 6. As is usual, the oven consists of the outer side wall 7 and an outer back wall 8, and an outer wall 9 located adjacent the burners 2. The oven has also an inner side wall 10, an inner back wall 11 and an inner wall 12 located adjacent the wall 9. The walls 10 and 12 are provided with inner linings 13 and 14, which linings are preferably removable, the said linings being constructed to receive an ordinary grate, not shown, so that it may rest at different elevations on the ledges 15 that are formed on the inner linings of the oven. As here shown, is a suitable division plate 16, that divides the oven 6 so that the lower portion constitutes what is commonly referred to as the broiler 17. The broiler is also provided with a removable lining 18 at its outer side and a removable lining 19 at its inner side, both linings being provided with ledges 20 for the attachment of an ordinary grate, not shown.

In making a structure capable of being used for a right or left hand range, it is found necessary to shift the oven burner 21 laterally, and we provide a construction which permits this burner and its manifold 22 to be thus shifted laterally, depending upon whether it be used in a right hand or a left hand burner. Attention is directed to the fact that the outside wall 23 of the broiler portion 17, is longer than the inner wall 12, which necessarily throws the opening 24 for the manifold 22 out of line when it is used for a right hand or a left hand range. When the parts are to be used for a left hand range, the outer wall 7 being

bolted in place as is usual in stoves, by means of suitable bolts 25, it is moved over to the left, hand side of the range, and the same is likewise true of the inner wall 10. It will be noted that in lifting these walls or linings 7 and 10 over to the other side of the range to be used as a left hand range, they will be turned around. It will also be noted that the door 26 will simply be shifted from right hand to the left hand side of the oven, and that the burner 2 and manifold 3, 4 and 5 will be shifted to the right hand side of the range. The rear walls 8 and 11 will also be lifted over to the left hand side of the range and the walls 9 and 12 will be turned end for end horizontally to form the inner walls 9, 12, 23 and 27 and will be turned around horizontally to form the inner walls of the oven and the broiler. This will shift the opening 24 to the opposite side of the center occupied by it when it was being used for a right hand range, thus making it essential that the burner and its manifold 22 be shifted laterally to accommodate themselves to the changed position of the opening 24. The manifold 22 has its outer end fitting loosely on its connection with the manifold 4, and its inner end 28 loosely fitting in an opening 29 of the burner feeding manifold 30. The form of burner 21, here shown, has its opening 32 located at the under side of the burner, and the outer wall of the burner 21 is provided with projecting ears 33, located at the rear end of the burner. In order to support the burner 21 from its outer side by its ears 33, it is essential to provide brackets so constructed that they are reversible so as to accommodate themselves to the changed positions of the burner. These brackets are shown in Figs. 1 and 6, and are designated by the numeral 34, and have their outer ends constructed with upper and lower ears 35 and oppositely projecting horizontal ears 36. By this arrangement when the bracket is in the position shown in Figs. 1 and 6, the lower ear 35 fits into an opening 37 formed in a flange 38 that extends outward from the lining 18, to which lining it is rigidly connected. The ears 35 are provided with openings 39, whereby when the bracket is in position in the opening 37 a cotter pin 40 is passed through the lower opening 39, thus holding the bracket to the flange 38. The opposite end of this bracket has a lateral projection 41, and this projection has a bolt opening 42 that registers with the bolt opening 43 formed in the burner ears 33. Referring to Fig. 1, which shows the burner in position for a right hand range, when it is used for a left hand range, it must be turned around and the manifold 22 must likewise be turned around, and when it is in this turned around position, owing to the changed location of the burner, the brackets

34 are turned over so that the ear 41 will rest under the ears 33, and the projection 41 extend in the opposite position horizontally to accommodate itself to the changed position of the burner 21. 70

Likewise it is necessary that the inner wall 27, of the broiler portion 17 of the oven, be constructed with a horizontal elongated opening 44, whereby the burner manifold 22 may have its changed position of the opening 24 and the manifold still pass through the wall 27. 75

The wall 23 is provided with suitable bolt openings 45, which are shown here as located in its corners, and likewise all of the other walls of the gas range will be provided with bolt openings and bolts, whereby they may be made to occupy a position to construct a right or a left hand oven range. 80

By reference to Fig. 5, the parts are shown in their disassembled relation, looking at them from the rear side of the gas range. In this view a panel portion 46 is located back of the burners 2 and under this panel is a lower panel 47, the top of the oven being shown at 48, Fig. 5. 85

It will be noted that the top of the oven has depending flanges 49, and the upper edge 50 of the wall 8 and the flanges 49 are provided with registering bolt openings 51, which serve to unite the two together. Likewise, the wall 7 has its upper edge 52 bent laterally and adapted to fit inside the flanges 49 of the top 48, the flanges being provided with registering bolt openings 53. Without adding to the numerals of the drawings, it is mentioned that from Fig. 5, it will be noted that the flanges at their lower edges and sides are provided with bolt openings, whereby all of the parts constituting the gas range may be changed from the right hand to the left hand side thereof to constitute either a right hand or left hand oven range. 95 100 105

By reference to Fig. 2, it will be observed that the burner top 54 has attached at its inner side a bracket 55, which extends downwardly, its upper end being bolted to the flange of the burner top and its lower edge being bolted to the projection 56, located on the manifold 22. 110 115

The top 48 of the oven is constructed with an inner wall 57, and the top can be bodily lifted to its proper position when the oven is changed to a left hand oven. 120

By reference to Fig. 5, it will be noted that the outer walls 7 and 8 extend throughout the height of the range, whether it be used in connection with a right or left hand oven. 125

It will be noted that the burner 21 has its gas inlet centrally located, whereby the turning of the burner, as is necessary for either a right or left hand burner, will always bring the gas opening in the center of the burner for supplying fuel thereto. 130

Attention is called to the fact that in gas

ovens, as is true with the oven here shown, the double wall at the back of the oven occupies more space therein than does the wall of the door 26, the door having its outer wall 5 located outside of and out of line with the walls of the oven, whereas the double wall at the rear of the oven is located so that the double walls 8 and 11 occupy greater oven space than does the inner wall of the said 10 door. This is the reason why the burner must change its position laterally according to whether it is used for a right or left hand oven.

The shiftable supports are designed to 15 equalize the difference due to the changed position of the burner, according to whether it is utilized for a right or left hand oven.

Having thus described our invention, what we claim and desire to secure by Letters Patent is:

1. A gas range comprising an oven and an open burner part, said oven having a reversible burner with a central gas opening, the open top having a manifold, and a 25 single oven burner manifold extending from the said open burner manifold substantially to the center of the oven and through its walls and connected with the oven burner, whereby the burner may be reversed and 30 placed in position for either a right or left hand oven without any change in their construction.

2. A gas range comprising an open burner portion and an oven portion located at one 35 side of the said burner portion, the oven portion having a burner with a central fuel supply opening, a manifold for the open burner portion, and a single L-shaped manifold connected with the burner manifold, the inner wall of the oven having an opening located slightly out of center between the edges thereof, and the outer end of the burner provided with reversible supports 40 adapted to be turned to accommodate the burner whether used in a right or left hand range.

3. A gas range comprising an open burner portion having a fuel manifold, an oven portion at one side thereof having double walls, the outermost wall being of greater horizontal area than the inner wall, the last mentioned wall having an opening slightly out of horizontal center, a reversible burner in the oven having its outer end provided with reversible supports adapted to accommodate themselves to the burner whether used in a right or left hand oven, and a single oven burner manifold extending from the open 55 burner manifold through the said wall opening and communicating with the central fuel feed, whereby the gas range is adapted for a right or a left hand oven.

4. A gas range comprising an oven, a 60 burner portion at one side thereof, an oven portion at the other side thereof constructed

of double walls, the side wall and the rear wall extending continuously throughout the oven and the outside inner wall made into detachable upper and lower portions, the lower portion having an opening slightly 70 out of center between its front and rear edges, a reversible burner located in the said oven having a central fuel feed and a single manifold extending through the said opening and communicating with a burner, the 75 opposite edge of the burner having reversible supports whereby the parts may be used in constructing either a right or left hand oven range.

5. A gas range comprising an open burner portion located at one side of the range and having a gas manifold, an oven located at the other side of the range, the oven having its rear double wall and its front having a door, the double wall occupying greater 80 oven space than does the door, a reversible oven burner located therein having a central fuel opening, a single reversible manifold extending through a opening in the innermost wall of the oven and communicating with the said fuel opening of the burner, and reversible brackets having one end with lateral extensions whereby they may be shifted to accommodate themselves 85 to the horizontal shifted position of the 90 said oven burner according to whether it is used in a right or left hand range.

6. A range comprising an open burner top part located at one side of the range, an oven portion located at the opposite side of the range, the rear and two side portions comprising doubled walled parts, and a door at its front side, the inner wall having a manifold opening, a burner located in the oven and having a central fuel opening at 100 its inner side, reversible brackets having laterally extending ends attached to the outer side of the oven burner and attached to the inner wall of the oven, whereby the brackets 105 may be reversed to accommodate themselves 110 to the changed position of the burner whether it be used in a right or left hand range, and a reversible manifold connected with the oven burner.

7. In a gas range, an open burner portion located at one side of the range and an oven portion at the other side of the range, the walls of the oven and of the open part of the range being detachable and shiftable to the opposite side of the range, a burner located 115 in the oven portion, an oven burner manifold extending from the front of the range to substantially the central portion of the open part of the range and then through 120 openings in the inner double wall of the oven to the said burner, the said burner and manifold being reversible, whereby the whole 125 structure may be constructed as either a right or left hand oven range.

8. A gas range comprising an open burner

constructed at one side of the range, an oven structure at the other side of the range, said rear wall of the oven structure being in one detachable piece and the rear wall of the open burner construction in two detachable pieces and the side walls of the oven structure made detachable and adapted to be used for a right or left hand oven range, a reversible oven burner supported in the oven, 10 a reversible manifold extending from the front to substantially the center of the open burner structure and thence at right angles through the wall of the oven and connected with the said reversible burner, and detachable brackets holding the said burner, whereby the structure including the said burner and manifold may be shifted and the range built as either a right or a left hand oven range. 15

In testimony whereof, we hereunto affix our signatures.
